UNITED STATES PATENT OFFICE

1,934,796

APPARATUS FOR MOISTENING THREADS

Alfred Friederich, Berlin, Germany, assignor to
Aceta G. m. b. H., Berlin-Lichtenberg, Ger-
many, a corporation of Germany

Application May 20, 1930, Serial No. 454,128, and
in Germany May 23, 1929

3 Claims. (Cl. 91—43)

The present invention relates to a device for the uniform wetting of threads and more particularly of artificial threads made according to a dry spinning process which before being worked up into textile materials, are provided on their surface with a wetting or lubricating agent rendering them supple for the following operations. Additional objects of my invention will be seen from the detailed specification following hereafter.

According to my invention, a regular wetting of a large number of threads with equal amounts of the liquid to be impregnated and without loss of the latter is obtained by supplying each lubricating or wetting device of a form described hereafter, automatically under pressure with exactly the amount of liquid calculated to be applied to the thread. The thread receives the wetting liquid directly at or below a narrow bore-hole from which the liquid flows out. The device according to this invention makes it possible that not a drop of the liquid is lost and that the same amount of liquid is forcibly transmitted to the thread in each unit of time. The uniform distribution of liquid delivered on a large number of lubricating devices is secured by mounting before the orifice of each device a throttle resistance of exactly the same size and of such a diameter that the other resistances may be neglected.

The accompanying drawing illustrates the process and the device according to the invention.

Figs. 1 and 2 are a front view and an end view respectively of the lubricating system having a large number of lubricating points.

Figs. 3 to 5 illustrate a special form of construction of the lubricating device in which the thread receives the wetting liquid directly at the orifice.

Figs. 6, 7 and 8 show another form of the device in which the thread receives the liquid ejected from the orifice at an edge below the latter.

In Fig. 1 *a* is the pressure piping for the wetting liquid which extends the whole length of the spinning machine. Pipes *b* branch off at distances corresponding with the single spinning places. Each of these branches *b* has a wetting nozzle *c* against which the thread *d* travels in a slight bend or break, if necessary. Having passed the wetting nozzle the thread is wound, for instance, on a spool *e* or on any other collecting or winding-on device. The piping *a* contains a manometer *f* for the purpose of ascertaining that the prescribed pressure of the liquid is maintained.

Fig. 3 is a plan and Fig. 4 a longitudinal section, Fig. 5 a front view of the lubricating nozzle. Each nozzle has exactly the same narrow bore of about 0,1 to 1 mm. diameter over whose opening *g* the thread *d* is passed. The front part *h* of the nozzle has the form of a notch in order to prevent the thread from leaving the nozzle. The thread *d* constantly receives from the orifice *g* exactly the amount of liquid which flows out therefrom under the pressure existing in the piping *a*.

The pressure maintained in the piping *a*, obviously, is dependent from the quantity of liquid to be delivered on the thread, from the viscosity of the liquid and, finally, from the diameter of the bore in the nozzle. It may be varied according to the specific circumstances from about 0,01 atmospheres to about 0,1 atmospheres.

Figs. 6, 7 and 8 show an alternative form of the nozzle. Fig. 6 is a plan, Fig. 7 a longitudinal section and Fig. 8 a front view. For the purpose of varying the amount of liquid which is ejected from the nozzle, without varying the pressure in the piping, and for simplifying the manufacture of the nozzle device itself, exchangeable cylindrical capillaries *i* of equal bore and length regulating the resistance of flow through the nozzle are fitted into the latter. The liquid flowing out from the boring *g* is collected at a striking edge *k*, whence it reaches the thread *d* in an uninterrupted and uniform manner.

The pressure piping *a* is connected with a supply vessel containing the liquid to be applied on the threads. By a suitable pump a uniform pressure regulated, if necessary, by a valve, is maintained in the device controlled by the manometer *f*. These pressure devices known in the art, are not shown in the drawing.

Numerous other embodiments are possible and I contemplate as included within my invention all such modifications and equivalents as fall in the scope of the appended claims.

What I claim is:—

1. A device for regularly wetting or lubricating a plurality of threads comprising a system consisting of a main conduit, a plurality of branch conduits connected with said main conduit and terminating in a plurality of means for discharging liquid therethrough and for simultaneously providing the sole restraint to the uncontrolled discharge of said liquid from said system, and means for providing said main conduit with liquid under pressure, each of said discharging and restraining means being a nozzle having therethrough a capillary bore of substantial length.

2. A device for regularly wetting or lubricating a plurality of threads comprising a system consisting of a main conduit, a plurality of branch conduits connected with said main conduit and terminating in a plurality of means for discharging liquid therethrough and for simultaneously providing the sole restraint to the uncontrolled discharge of said liquid from said system, and means for providing said main conduit with liquid under pressure, each of said discharging and restraining means being a nozzle having therethrough a capillary bore of substantial length and bearing at its bore a guide for the thread.
3. A device for regularly wetting or lubricating a plurality of threads comprising a system

consisting of a main conduit, a plurality of branch conduits connected with said main conduit and terminating in a plurality of means for discharging liquid therethrough and for simultaneously providing the sole restraint to the uncontrolled discharge of said liquid from said system, and means for providing said main conduit with liquid under pressure, each of said discharging and restraining means being a nozzle having therethrough a capillary bore of substantial length and of about 0.1 to 1 mm. diameter and exerting a relatively high resistance to the outflow of the liquid and bearing at its bore a guide for the thread.
